ABSTRACT OF THE DISCLOSURE

Method and apparatus for measuring the substance cross-section of textile material, slivers in particular, in which the textile material is drawn at a predetermined speed through a nozzle having at least one constriction, pneumatic pressure generated at the constriction being evaluated as the measured quantity relating to the substance cross-section of the textile material.

Background of the invention

Suitable measuring systems for determining substance cross-section of textile material are extremely important to quality control in the textile industry insofar as they enable the manufacturing processes to be monitored and regulated on the basis of the results that are provided. At present, the only measuring systems of this type in common use are capacitive and optical measuring systems. The principal disadvantage of a capacitive system is that it is sensitive to the moisture content of the textile material and therefore does not provide consistently accurate measurement. In addition to this, the zero or neutral point is not stable enough to insure dependability of operation. In optical measuring systems, difficulties are encountered due to lack of stability in both phototransmitters and photo-receivers. In addition to capacitive and optical measuring systems, it has already been proposed as a result of extensive tests to take measurements on the principle of the absorption of radio-active rays by the textile material. Unfortunately, none of these proposals has had any practical applications for a variety of reasons.

Brief description of the invention

The present invention has an object to obviate the disadvantages inherent in known devices, as indicated above, and relates to a method of obtaining measurements corresponding to the substance cross-section of textile material, slivers in particular, in which the textile material is drawn at a predetermined speed through a nozzle having at least one constriction, pneumatic pressure generated at the constriction being evaluated as the measured quantity relating to the substance cross-section of the textile material. The invention also provides an apparatus for carrying out this method, comprising a nozzle through which the textile material can travel and which tapers in cross-section in the direction of movement of the textile material and has a hollow or empty space between two planes lying one behind the other, extending vertically of its axis, and a manometer connected to this empty space for determining a quantity relating to the pneumatic pressure in the hollow or empty space.

It is an object of the present invention to provide method and apparatus for obtaining measurements of the substance cross-section of textile material which is dependable and consistently accurate in operation.

It is another object of the present invention to provide a method and apparatus as described wherein variable

2

properties of air, such as temperature and pressure, are eliminated automatically as factors in the measurement.

It is a further object of the present invention to provide a method and apparatus as described wherein the measurement of a sliver of textile material is accomplished by measurement of the air derived from abrupt reduction in the cross-section of the sliver.

It is an object of the present invention to provide an apparatus of the type described which is capable of producing a measurement independent of the rate of movement of the sliver of textile material.

These and other objects, features and advantages of the present invention will become more apparent from the following detailed description thereof when taken in conjunction with the accompanying drawings wherein:

FIGURE 1 shows a cross-section of a basic nozzle arrangement in accordance with the invention,

FIGURE 2 is a section through a funnel-shaped nozzle (trumpet),

FIGURE 3 shows a trumpet of the kind shown in FIGURE 2 with an annular widened portion,

FIGURE 4 shows a trumpet with groove machined into it, and

FIGURE 5 shows a measuring system with a nozzle and pressure compensation in accordance with the invention.

Detailed description of the invention

In the method according to the invention, textile material 5 is drawn through two substantially concentric apertures 1 and 2 lying one behind the other, as shown in FIGURE 1. The aperture 2 is smaller in diameter than the aperture 1 so that after passing through the aperture 1, the textile material is compressed by the aperture 2. A certain amount of air is trapped in the constituent fibrous material of the sliver, and passes through the apertures together with the textile material. If the fibre cross-section is the same in both the apertures 1 and 2, a quantity of air which corresponds both to the rate of flow of the textile material and to the difference in cross-section of the two apertures, must be forced out of the mass of fibres during passage from the aperture 1 to aperture 2. This air escapes into the chamber 3, if possible; however, if the chamber 3 is completely, or at least partly, closed, all or part of the air must escape longitudinally through the sliver.

Fairly large substance cross-section generates a fairly high air resistance and accordingly a relatively high pressure in the chamber 3 which can be detected through a manometer, for example, connected to the chamber at an opening 4 in this chamber. The air resistance could of course also be measured with compressed air introduced into the chamber. In the present method, however, the measuring medium itself supplies an active quantity of air pressure, which must be regarded as a substantial advantage.

Elements for constricting the fibre-cross-section of slivers are known per se and are commonly used in many textile machines, being referred to therein as condensers or trumpets. FIGURE 2 is a section through one embodiment of such a trumpet having a central passage which is reduced continuously in cross-section. It is of particular advantage to design these trumpets in accordance with the present invention wherein the central passage is provided with successive concentric apertures of different size producing an abrupt reduction in the passage so that they can be used as measuring elements, as shown in FIGURE 3. An annular widened portion 7 is provided in the wall of the trumpet in such a way that a first cross-section has a diameter d_1 and a second cross-section a smaller diameter d_2 . The widened portion 7 may com-

municate with a manometer or other measuring device (not shown) through a nipple 6.

A particularly simple form of trumpet, as seen in FIGURE 4, is obtained by machining a groove 8 into the walls of the central passage and providing a radial bore 9 in communication therewith for the connection of a pressure gauge to the chamber formed by the groove 8. Of course, other nozzle configurations may be provided utilizing the principles set forth herein without departing from the spirit and scope of the present invention.

The pressure generated in the chamber 3 is, however, not only governed by the extent to which the sliver is constricted as it passes from the aperture 1 to the aperture 2, but also by the rate at which the sliver is pulled through the nozzle. To allow for this factor in the measurement, a unit of the kind shown in FIGURE 5, for example, may be provided for producing a differential measurement; it comprises an air compressor 14 driven at a rotational speed proportional to the rate of passage of the sliver 5 through the nozzle 11. If the pressure generated in the compressor 14 is applied in opposition to the pressure in the chamber 3, selectively through a regulating valve 13, for example in a differential manometer 12, the ratio between the pressure in the chamber 3 as applied to arm 15 of the manometer, and the pressure in the arm 16 of the manometer 12 derived from compressor 14 via valve 13 will provide an indication of the substance cross-section. The differential method using a compressor 14 is also of advantage insofar as the variable properties of the air, such as temperature and barometric pressure, are automatically taken into consideration and eliminated as factors in the measurement.

In cases where a regulating system is used, the regulating valve 13 also enables a desired value to be set for the substance cross-section to be measured in that a rise in pressure in the arm 16 requires an increasing substance cross-section in the trumpet 11 and vice versa.

In order to derive a signal from the pressure difference measured in the manometer 12, a suitable converter means 18 known per se may be provided which converts the level of the manometer column 17 or its fluctuations into a suitable measured quantity which may be obtained as an electrical signal.

I have shown and described several embodiments in accordance with the present invention. It is understood that the same is not limited thereto but is susceptible of numerous changes and modifications as known to a person skilled in the art and I, therefore, do not wish to be limited to the details shown and described herein.

I claim:

1. A method of obtaining measurements corresponding to the substance cross-section of a sliver of textile material comprising

guiding the textile material through a nozzle having at least one relatively abrupt constriction in cross-section, whereby air is discharged from the textile material at said constriction, and

measuring the air pressure generated by said discharge of air at said constriction.

2. A method as defined in claim 1 wherein said step of measuring includes providing a counter air pressure corresponding to the desired value of the substance cross-section of the textile material and comparing the generated air pressure with the counter air pressure to obtain a resultant value.

3. A method as defined in claim 2 further comprising converting said resultant value to an electrical signal.

4. A method of obtaining measurements corresponding to the substance cross-section of textile material, slivers in particular, comprising

moving said textile material at a prescribed rate along a given path, abruptly restricting the cross-section of said textile material at a point along said path, and

measuring the pressure of the air forced out from said textile material as a result of the restriction of the cross-section thereof.

5. A method as defined in claim 4 further comprising the steps of providing a counter air pressure having a magnitude proportional to the rate of movement of the textile material and comparing the emitted air pressure with the counter air pressure to obtain a resultant value.

6. A method as defined in claim 5 further comprising converting said resultant value to an electrical signal.

7. An apparatus for obtaining measurements corresponding to the substance cross-section of textile material, slivers in particular, comprising

a nozzle having a central through-passage, said through-passage having a relatively abrupt reduction in cross-section at an area along its length in the direction of movement of textile material therethrough, and measuring means connected to said nozzle for measuring the air pressure created in said through-passage at the point of said abrupt reduction in cross-section by the compression of said textile material by said abrupt reduction in cross-section.

8. An apparatus as defined in claim 7 wherein said through-passage tapers gradually toward its axis from one end to the other in the direction of movement of textile material therethrough with the exception of said area of abrupt change in cross-section.

9. An apparatus as defined in claim 7 wherein said nozzle further includes a chamber positioned between two parallel planes transverse to the axis of said through-passage at the area of abrupt reduction in cross-section thereof, said measuring means being connected to said chamber.

10. An apparatus as defined in claim 9 wherein said through-passage tapers gradually toward its axis and said chamber is provided as an annular groove in the surface of said through-passage.

11. An apparatus as defined in claim 10 wherein said nozzle further includes a transverse bore communicating with said chamber, said measuring means being connected to said bore.

12. An apparatus as defined in claim 9 wherein said measuring means includes a differential manometer having a first inlet connected to said chamber and a second inlet, a compressor providing a counter air pressure connected to the second inlet of said manometer.

13. An apparatus as defined in claim 12 wherein said measuring means further includes a regulating valve connected between said compressor and said second inlet of said manometer.

14. An apparatus as defined in claim 13 wherein said measuring means further includes converter means for converting the reading of said manometer into measured quantities corresponding to the substance cross-section of the textile material.

15. An apparatus as defined in claim 7 wherein said measuring means includes a manometer connected to said nozzle for measuring air pressure in said through-passage.
